UNITED STATES PATENT OFFICE.

JOSEPH B. LARKIN, OF PALO ALTO, CALIFORNIA.

LUNCH-COUNTER TICKET.

1,408,103.

Specification of Letters Patent. Patented Feb. 28, 1922.

Application filed October 29, 1921. Serial No. 511,428.

To all whom it may concern:

Be it known that I, JOSEPH B. LARKIN, a citizen of the United States, and resident of Palo Alto, in the county of Santa Clara and State of California, have invented certain new and useful Improvements in Lunch-Counter Tickets, of which the following is a specification.

This invention relates to a lunch counter ticket adapted to be used in conjunction with the device set forth in my copending application, Serial No. 465056, filed April 27, 1921.

It is the object of my invention to provide a ticket of the character indicated that not only carries desired figures in proper sequence, but also is provided with a punching blank adjacent each figure and has means formed therein for engagement with a mechanical positioning element. The tickets are preferably duplicated in a roll and serially numbered.

In the drawing,—

Figure 1 is a plan view of the device, part broken away.

Figure 2 is a side elevation of the same.

Figure 3 is a plan view of the tickets used in this device.

Figure 4 is a side elevation of the key used to punch the tickets.

Referring more particularly to the drawing, 1 indicates a rectangular metal case with a plurality of spaced orifices as 4 in its upper side. At 5 is a flange depending from the lower side of case 1 and supporting a roll of printed blanks 6, the said roll being held in position thereon by a bolt and nut as at 7. Each printed blank has a plurality of spaced rings as at 8 printed thereon in exactly the same spaced relation as the orifices in case 1, these rings being numbered consecutively as at 9 from five to one-hundred and fifty, and representing purchases of five cents and multiples thereof up to one dollar and fifty cents. Between each two printed blanks on the strip and on the perforated division thereof is an orifice 10 for the purpose hereinafter set forth.

Across the upper surface of case 1 are arranged two guide members 11 connected by a wire 12. At 13 is shown a spring mounted on the under side of the top of case 1 and provided with pins 14 and 15 passing through orifices 16 and 17 into top of case 1.

In operation the strip of printed blanks

is fed through guides 11 and drawn forward until pin 14 engages orifice 10 in the printed strip. This is so arranged with relation to circles 8 that when engaged by pin 14 each circle is in alignment with one of the orifices 4 in case 1. If the order amounts to ten cents the waiter takes a punch as 18 having a square end as shown, and punches out the circle having the figure "10" thereover. If another purchase is made (say twenty cents), the amount is added to the amount already punched and the circle under the figure "30" is punched out. If the service to that customer is now finished the waiter presses down on pin 15 (over which strip 6 slides easily) thereby withdrawing pin 14 from orifice 10, and pulls the strip along through guides 11—11 until pin 14 engages the next orifice 10. The withdrawn portion is now torn from the balance of the strip along the edge of the adjacent guide 11 and handed to the customer who pays the highest amount punched thereon.

This device is always in view of the customer who sees the total amount to be paid at the first service to him, and each addition thereto if additional service is rendered. The wire 12 prevents removal of the check before additional blanks are arranged in position. The arrangement of pins 14 and 15 provide a simple and effective means for effecting a perfect alignment of circles and orifices. The whole device is simple and compact in form, easily operated and highly efficient in its practical application. The orifice 10 being formed on the perforated divisions between the checks also render their separation easy, accurate and positive.

I claim:—

A device of the character indicated comprising a long strip of paper divided by equidistant transverse lines of perforations into successive uniform sections, each section carrying two rows of parallel spaced and consecutively arranged members beginning with the numeral five and proceeding in multiples thereof, and two rows of correspondingly spaced and parallel circles indicating portions of the paper to be punched out, a circle being arranged adjacent to each number, and said strip having an orifice formed therein in each line of perforations.

JOSEPH B. LARKIN.
